UNITED STATES PATENT OFFICE.

ANDREW TURNBULL, OF NEW BRITAIN, CONNECTICUT, ASSIGNOR TO THE NATIONAL WIRE-MATTRESS COMPANY, OF SAME PLACE.

IMPROVEMENT IN BED-BOTTOMS.

Specification forming part of Letters Patent No. **137,511**, dated April 1, 1873; application filed November 22, 1872.

To all whom it may concern:

Be it known that I, ANDREW TURNBULL, of New Britain, in the county of Hartford and State of Connecticut, have invented a new Improvement in Spring Bed-Bottoms; and I do hereby declare the following, when taken in connection with the accompanying drawing and the letters of reference marked thereon, to be a full, clear, and exact description of the same, and which said drawing constitutes part of this specification, and represents, in—

Figure 1, a side view showing the cross-bar in transverse section; Fig. 2, a top view; and in Fig. 3, a longitudinal section on line *x x*.

This invention relates to an improvement in that class of spring bed-bottoms in which the springs are attached to a cross-bar at the head and foot; the object being to adjust the springs to a greater or less tension. The invention consists in making one or both of the cross-bars adjustable in a support at the ends, as more fully hereinafter described.

A represents one side of the bed-frame, usually formed from wood. At the end of this frame is fixed a support, B, for the cross-bar C, the cross-bar being preferably set above the side A, as seen in Fig. 1. The support B is chambered out to receive the end of the bar C, as seen in Figs. 1 and 3, and through this

chamber a longitudinal screw, D, is placed, passing through the bar C, a nut, *a*, set into the bar, in which nut the screw works; therefore, by turning the screw D, the bar C will be drawn back or thrown forward, accordingly as the screw is turned. The bed-bottom attached to the cross-bars may be drawn up to the desired degree of tension by means of the screw, and that tension slackened at any time by the loosening of the screw.

By preference I form both ends in this manner, but the object will be accomplished by making one of the bars stationary and the other adjustable, in the manner described.

I do not wish to be understood as broadly claiming the arrangement of adjusting-screws for the purpose of adjusting the tension of the springs, as such I am aware is not new.

I claim as my invention—

The cross-bar C of a bed-bottom frame, each end arranged in a support, B, attached to the side A, and made adjustable in said support by means of a screw, D, substantially in the manner set forth.

ANDREW TURNBULL.
